Prosecution History of co-owned U.S. Pat. No. D617163, filed Aug. 26, 2009.

Primary Examiner — Randall Gholson

CLAIM

The ornamental design for a torque wrench for ultrasonic instrument, as shown and described.

DESCRIPTION

FIG. 1 is a top perspective view of a torque wrench for ultrasonic instrument;

FIG. 2 is a top plan view thereof;

FIG. 3 is a side elevation view thereof;

FIG. 4 is a front end plan view thereof; and,

FIG. 5 is a back end plan view thereof.

The broken lines shown in the drawings are included for the purpose of illustrating structural environment and form no part of the claimed design.
